(57) **CLAIM**

The ornamental design for a drain stopper, as shown and described.

DESCRIPTION

FIG. 1 is a front, top perspective view of a drain stopper, showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines in the figures are for the purposes of illustrating portions of the drain stopper and form no part of the claimed design.

The short-short-long dashed broken lines immediately adjacent to the claim area in the figures are for the purposes of illustrating the boundaries of the drain stopper, and form no part of the claimed design.
